UNITED STATES PATENT OFFICE

WILLIAM E. DUNNING, OF ALLIANCE, OHIO, ASSIGNOR TO THE McCASKEY REGISTER COMPANY, OF ALLIANCE, OHIO, A CORPORATION OF OHIO

AUTOGRAPHIC REGISTER

Application filed February 8, 1930. Serial No. 427,025.

The invention relates to autographic registers, and more particularly to that type of machine in which a plurality of strips of paper, or the like, are fed across a table, means being interposed between the strips for transferring records made upon the top strip to the under strip or strips.

The object of the improvement is to provide a machine of the character referred to in which the plural strips, or packets, of paper are perforated at spaced intervals, or otherwise arranged to be separated into individual slips or tickets, and in which each slip or ticket is provided with an opening near its upper end for properly positioning the paper strips at the completion of each operation of the machine.

A still further object is to provide a feed mechanism including a pair of feed rolls for feeding the paper strips through the machine, and cam means for automatically separating the feed rolls at the end of each operation of the machine in order to permit proper aligning of the strips before each set of tickets or slips is torn therefrom.

Still another object of the invention is to provide an aligning mechanism adapted to engage the strips at the completion of each operation of the machine; and to provide a stop lever for limiting the movement of the operating handle for the feed rolls; means being provided for withdrawing the aligning mechanism from engagement with the strips when the stop lever is moved out of the path of the operating handle.

Other objects of the invention will be pointed out in the following detailed description of an illustrative but preferred embodiment of the invention, or will be obvious in connection therewith.

For a more complete understanding of the nature and objects of the invention, reference is had to the accompanying drawings, showing a preferred embodiment of the invention, in which:

Figure 1 is a side elevation of a machine constructed in accordance with the invention;

Fig. 2, a vertical, longitudinal section through the improved machine;

Fig. 3, a plan view of the machine with the top or cover removed;

Fig. 4, a detail section of the drive ratchets and pawls, taken on the line 4—4, Fig. 3, shown on a larger scale;

Fig. 5, a similar view of the drive gears for the feed rolls, showing one of the cams for separating the feed rolls at the completion of each operation of the machine;

Fig. 6, a top plan view of the machine;

Fig. 7, a detached perspective view of the driving, feeding and aligning mechanism, the parts being separated, and broken away in places, for the purpose of illustration;

Fig. 8, a view of a portion of a plural strip, for use in the machine, showing the manner in which it may be folded to form a plurality of strips, and the manner in which certain of the strips may be provided with carbonized surfaces;

Fig. 9, a transverse section through the record strip, showing the same folded in the manner in which it is stored in the storage compartment of the machine, and before it is cut by the knife;

Fig. 10, a fragmentary transverse section as on the line 10—10, Fig. 3, showing the manner in which the knife cuts the several strips apart at their side edges, as the plural strip is fed through the machine; and

Figs. 11, 12 and 13, views similar to Fig. 10, showing different methods of folding the strip.

Referring to the embodiment of the invention illustrated in the drawings, a casing 10 is provided for housing the operating parts of the machine, the side and end walls of the casing being preferably formed of sheet metal and mounted upon a wood base, as shown at 11.

The interior of the casing may be divided, as by the partition walls 12, into compartments 13 and 14, the compartment 13 being employed for housing a storage supply of record strips as indicated generally at 15, while the compartment 14, may be used for filing the lowermost strip after records have been written thereon, as indicated at 16 in Fig. 2.

Each of the partition walls 12 may prefer-

ably be formed of sheet metal, having an angle flange 17 at its lower end for attachment to the wood base, as by screws 18, and the upper ends of the partition walls may be curved outward, as shown in Fig. 2, thus permitting the record strips to be easily placed in the compartments.

The record strip which is used in the machine may be any suitable form of plural strip, adapted to make duplicate, triplicate or any plurality of copies, and is preferably of the type shown in Figures 8, 9 and 10 of the drawings.

As shown in these figures the several strips are formed in a single sheet adapted to be folded longitudinally upon itself to form the desired number of strips, three being shown for the purpose of illustration. The sheet is adapted to be folded along the dotted lines 19, dividing it into the three record strips 20, 21 and 22, of equal width.

Each strip may be divided, by perforations or the like, as shown at 23, into slips or tickets upon which any desired items may be recorded, and any suitable printed form may be provided upon each slip.

Because of the manner in which the record strips are folded, these printed forms, as shown at 24, in Fig. 8, may be placed on one side of the outer strips 20 and 22, and on the opposite side of the central strip 21. This will be obvious from an inspection of Fig. 9, in which it is seen that when the sheet is folded, for use in the machine the central portion 21 becomes the lower strip, while the side strips 20 and 22 are each folded over upon the central strip.

For the purpose of recording writings on to the top strip, upon the under strips, sheets of carbon paper may be interposed between the strips, in a manner which will be later described, or certain of the strips may be provided with carbonized under surfaces. As shown in Fig. 8, the reverse sides of the strips 20 and 22 may be carbonized, so that when folded, as in Figs. 9 and 10, a writing upon the upper strip 20 will be recorded upon the under strips 22 and 21.

The plural record strip is folded back and forth, upon the transverse lines 23, and stored in the compartment 13, as shown in Fig. 2. The upper end of the strip is passed rearward and around the roll 25, located in the upper, rear corner of the casing, and beneath the spring 26, carried by the cover hinge rod 77 of the casing.

After passing between the roll and spring, the record strip is carried forward, and over the knife 28, shaped as shown in Fig. 3, with the central, rearwardly disposed reduced portion 29, and the reversely curved side edges 30, whereby the several strips are severed, along the lines 19, into separate strips.

The plurality of strips then passes forward, over the table 31, which is preferably

mounted in the cover, and beneath the sight opening 32 in the cover, through which one complete slip or ticket is adapted to be exposed at a time, to permit the operator to write therein for recording upon the several strips.

Forward of the opening 32 are located the upper and lower feed rolls 33 and 34 respectively, the upper roll being preferably carried in a housing 35, formed in the cover, and normally urged down toward the lower roll by means of springs 36, contacting with the upper roll shaft 37.

The lower feed roll 34, is fixed upon the shaft 38, journalled through opposite side walls of the casing, and adapted to be rotated, to drive the feed rolls as will be later described.

An operating handle 39 is provided for rotating the shaft 38, and may be provided with a boss 40, fixed upon the tubular shaft 41, which is journalled upon the shaft 38, as by the screw 42 located through the boss and tubular shaft and having the reduced end portion extended into the annular groove 43 formed in the shaft 38.

An arm 44 is fixed upon the tubular shaft 41 and has thereon the pawls 45 and 46, the pawl 45 being adapted to engage the ratchet 47, which is fixed to the adjacent side wall of the casing in any suitable manner, as by rivets or the like located through apertures 48 in the ratchet, and preferably spaced from said side wall as by the boss 49.

The handle 39 is thus normally held in the position shown in the drawings, the pawl 45 and ratchet 47 preventing the handle from falling by gravity to a vertical position. The pawl 46 is arranged to engage the ratchet 50, which is fixed upon the shaft 38, for the purpose of rotating said shaft through the handle.

A gear 51 is fixed upon the shaft 38, being preferably fixed to the ratchet 50, as by rivets or the like indicated at 52. This gear is adapted to mesh with the pinion 53, fixed upon the shaft 37, of the upper feed roll 33, so that both feed rolls will be rotated together when the handle 39 is operated.

Cams 54 are fixed upon the shaft 38, one near each end of the shaft, the cam adjacent to the handle end of the shaft being preferably attached to the ratchet 50 and gear 51 as by the rivets 52.

Each cam has a high point 55 adapted to engage the shaft 37 and move it upward, against the pressure of the springs 36, just before the handle reaches the stop position, shown in the drawings, in order to raise the upper feed roll out of contact with the record strips, at this point, and permit the strip aligning mechanism to function, as will be hereinafter described.

For the purpose of stopping the operating handle 39 in the position shown in the draw-

ings, at the completion of each operation, a thumb lever 56 is provided upon the adjacent side wall of the casing, and has the stop lug 57 thereon, adapted to contact with the stud or roller 58 upon the handle.

This thumb lever may be fixed upon the shaft, journaled through opposite side walls of the casing, and provided with the arm 60, fixed thereon, and normally urged toward the position shown in the drawings by means of the spring 61, which may be attached to the adjacent partition wall 12, or other stationary portion of the machine.

A link 62 connects the arm 60 with a rocker arm 63 fixed upon the hub 64, which is journaled upon the shaft 38, and has the oppositely disposed rocker arm 65 fixed thereon, the latter arm carrying a stud or roller 66.

Interposed between the hub 64 and the lower feed roll 34, is a collar 67, fixed upon the shaft 38, and having the curved arm 68 pivoted thereon, as at 69. This arm has the curved under surface 70 extending from adjacent the pivotal point to the point 71 from where cut away surface 72 extends outward to the free end of the arm. A spring 73 is connected to the end of the curved arm and to the collar 67 to normally urge said arm downward toward the stud or roller 66, which is adapted to engage the under surfaces 70 and 72 of the arm.

A stud 74, which may be in the form of a screw as shown in the drawings, or otherwise removable, is carried upon the upper side of the curved arm 68, and adapted to engage the apertures 75 in the record strips to properly position and align the strips prior to tearing off the slips or tickets upon which the last transaction has been recorded.

The cover 27 is provided with the depending side flanges 76, adapted to overlap the outer surfaces of the side walls of the casing and is pivoted at its rear end to the casing as by the rod 77. A curved separating and deflecting plate 78 is carried by the cover 27, just forward of the feed rolls, for separating the under strip from the upper strip or strips, and deflecting it downward into the filing compartment 14, while the upper strip or strips may be torn upon the cutting edge 79.

The front portion of the cover may be a separate member, as shown at 27a, and may be pivoted to the casing, at its forward end, as by the rod 80, the rear end being arranged to overlap the offset tongue 81 carried by the rear cover 27.

A latch is provided for normally holding the cover in position upon the casing, and may comprise the locking tongue 82, pivoted to one side wall of the casing, as at 83, and adapted to engage the depending lug 84, carried upon the inside of the front cover section 27a. For the purpose of normally holding the latch in locked position, an angular

arm 85 may be provided upon the latch, and normally urged downward, as by the spring 86.

A finger lever 87 may be connected to the latch, and located upon the outside of the casing for releasing the latch from engagement with the lug 84, when it is desired to remove the cover. A spring 88 may be located at the pivotal point of the front cover section 27a for urging said cover section into open position when the latch is released, permitting the operator to have access to the front edge of the main or rear cover section 27 to raise the same away from the casing.

As above described, the reverse sides of certain of the record strips may be carbonized, or if desired, sheets or strips of carbon paper may be interposed between the plural record strips as they pass over the table 31, to provide for recording upon the under strip or strips, of matter written upon the upper strip.

For this purpose a well 89 may be formed in the upper portion of one side wall of the casing, for housing a plural roll of carbon paper as shown at 90, the strips of carbon paper being interposed between the record strips and extended transversely across the machine.

In the operation of the machine the parts are normally in the position shown in the drawings, the operating handle being located against the stop lug 57, upon the thumb lever 56, which is held in this position by means of the spring 61.

By means of this same spring the roller or stud 66, upon the rocker arm 65, is held in engagement with the high portion 70 of the curved arm 68, holding said curved arm up, against the pull of the spring 73, so that the stud 74, upon the curved arm, engages the apertures 75 of the foremost slip or ticket portions of the recording strips. In this position, the cams 54, upon the shaft 38, and the spring 36, cooperate to hold the upper feed roll 33 down upon the lower feed roll 34, and in contact with the record strips.

The operator will write, through the opening 32, upon the exposed slip or ticket portion of the upper strip, the writing being recorded, in usual manner, upon the under strip or strips.

After the writing is completed the thumb lever will be pushed forward by the operator, moving the lug 57 away from the stop pin 91, and out of the path of the roller 58.

This movement of the thumb lever, through the shaft 59, throws the rocker arm 60 forward, and through the link 62 the rocker arm 65 is swung rearward, bringing the roller or stud 66 thereon out of engagement with the high part 70 of the curved arm 68, permitting the spring 73 to pull the curved arm downward and withdrawing the stud 74 from the apertures 75 in the record strips.

The operating handle 39 is then turned in

the direction of the arrow shown in Fig. 1 and when the same has cleared the stop lug 57 the thumb lever may be released so that the spring 61 will bring the associated parts 5 back to the normal position.

As the handle makes one complete revolution, the slip or ticket portions of the record strips, which have just been written upon, will be fed forward, the lowermost record 10 strip being deflected by the curved deflector 78 and fed downward into the filing compartment 14, while the upper strip or strips will pass outward over the cover.

Just before the handle completes a revolution and reaches the stop position, the high points 55 on the cams 54 will engage the shaft 37 and move it upward against the pressure of the springs 36, raising the upper feed roll out of contact with the strips. At this point 20 the roller 66 upon the rocker arm 65 is forcing the stud 74 into the apertures 75 of the foremost record strips, and the separation of the feed rolls permits the stud 74 to properly align the strips for subsequent detachment 25 at the cutting edge 79.

As the handle completes a revolution, the roller 58 thereon will again engage the stop lug 57 upon the thumb lever at which time the parts will all have moved back to the 30 position illustrated in the drawings, the stud 74 engaging the apertures in the next set of slips or tickets upon the record strip while the upper slip or slips which have been fed forwardly out of the machine may be torn off upon the cutting edge 79.

If it is desired to use record strips without the apertures 76 therein, the stud 74 may be removed, in which case the operation will be otherwise the same as above described.

40 A knob 92 may be provided upon the end of the shaft 38 opposite to the handle 39 for manually rotating the shaft if necessary from time to time to properly position the parts in order to align the record strips for writing 45 and tearing off at the proper place.

I claim:

1. An autographic register including a casing adapted to contain a plural record strip divided transversely into a plurality 50 of ticket portions having apertures therein, a table in the casing, feed rolls for feeding the plural record strip over said table, means for separating the feed rolls as each set of ticket portions reaches a predetermined position upon the table, a stud for engaging the apertures in the foremost ticket portions when the rolls are separated, an operating handle for the feed rolls, a movable stop for the handle, and spring means operatively 55 connected with the stop for withdrawing the stud from said apertures.

2. An autographic register including a casing adapted to contain a plural record strip divided transversely into a plurality of 60 ticket portions having apertures therein, a

table in the casing, feed rolls for feeding the plural record strip over said table, means for separating the feed rolls as each set of ticket portions reaches a predetermined position upon the table, a stud for engaging the apertures in the foremost ticket portions when the rolls are separated, an operating handle for the feed rolls, a movable stop for the handle, and spring means for withdrawing the stud from said apertures when the stop is moved out of the path of the handle. 70

3. An autographic register including a casing adapted to contain a plural record strip divided transversely into a plurality of ticket portions having apertures therein, a 80 table in the casing, feed rolls for feeding the plural record strip over said table, means for separating the feed rolls as each set of ticket portions reaches a predetermined position upon the table, a pivoted arm rotatable with one of the feed rolls, a stud upon said arm, lever means for moving said arm to engage said stud with the apertures in the foremost ticket portions when the rolls are separated, an operating handle for the feed rolls, a movable stop for the handle, and means operatively connected with the stop for withdrawing the stud from the apertures. 85

4. An autographic register including a casing adapted to contain a plural record strip divided transversely into a plurality of ticket portions having apertures therein, a table in the casing, feed rolls for feeding the plural record strip over said table, means for separating the feed rolls as each set of ticket 95 portions reaches a predetermined position upon the table, a pivoted arm rotatable with one of the feed rolls, a stud upon said arm, lever means for moving said arm to engage said stud with the apertures in the foremost ticket portions when the rolls are separated, an operating handle for the feed rolls, a movable stop for the handle, and means for withdrawing the stud from said apertures when the stop is moved out of the path of the handle. 100

In testimony that I claim the above, I have hereunto subscribed my name.

WILLIAM E. DUNNING.
